NOISELESS WINDOW GUIDE

Original Filed Aug. 7, 1922

FIG. 1

FIG. 2

FIG. 3

INVENTOR

George A. Reynolds

BY
Howard O. Denison
ATTORNEY.

UNITED STATES PATENT OFFICE.

GEORGE ALLEN REYNOLDS, JR., OF BINGHAMTON, NEW YORK.

NOISELESS WINDOW GUIDE.

Application filed August 7, 1922, Serial No. 580,365. Renewed August 8, 1924.

To all whom it may concern:

Be it known that I, GEORGE ALLEN REYNOLDS, Junior, of Binghamton, in the county of Broome, in the State of New York, have invented new and useful Improvements in Noiseless Window Guides, of which the following, taken in connection with the accompanying drawings, is a full, clear, and exact description.

10 This invention relates to a noiseless window guide of a class set forth in my pending application, Serial No. 568,736, filed June 16, 1922, and to the method of making the same except that instead of inserting the form 15 retaining wires into the felt guide strip before folding, the guide strip is first folded to the desired U-shaped cross-sectional form and then retained in that form by driving previously formed staples from the back into 20 to the opposite sides or flanges of the fold in such manner that the prongs of the staples will lie wholly within the surfaces of the guide flanges to prevent contact of the glass with the metal staples.

25 The object is to provide a more expeditious means for retaining the U-shaped form of a felt or equivalent window guide and at the same time preserving its longitudinal flexibility without exposing any parts of the 30 metal staples to contact with the glass.

Other objects and uses will be brought out in the following description:

In the drawings:

Figure 1 is a perspective view of a window guide embodying my invention.

Figure 2 is a transverse sectional view of the same.

Figure 3 is a perspective view of one of the detached staples.

40 As illustrated, this window guide comprises a strip —1— of felt or equivalent flexible material capable of being bent into U-shaped cross-sectional form, to afford the desired lengthwise channel —2—, for receiving the adjacent edge of a sliding window glass, not shown, but commonly used in the doors and panels of automobiles and analogous places.

That is, the strip —1—, of felt, is cut to 50 the required width upon a flat body of the same material, of any desired length, and while the strip is still flat, the central longitudinal portion of one side is channeled at —3—, to a width corresponding approximately to that required to form the channel —2—, thereby reducing the thickness of the

central longitudinal portion of the strip, to enable the thicker longitudinal edges, as —4—, to be opened in the same direction at substantially right angles to the central portion and thereby to form opposite side walls of the groove —2—.

If desired, the felt strip —1—, may be cut to a length sufficient to form the opposite upright sides and top of the window guide 65 and afterward bent into U-shaped form in a metal mold, as —A—, to impart the necessary symmetry thereto, and to facilitate the retention of the U-shaped cross-sectional form of the felt guide by the insertion of 70 a series of staples —5— thereinto from the back of the strip, so that the opposite arms of the staples may enter the opposite flanges of the strip between the inner and outer faces of said flanges. These staples are driven into 75 the felt strip in longitudinally spaced relation to preserve the longitudinal flexibility of the strip after it is bent into U-shaped form, while at the same time serving to retain the U-shaped form of the strip when removed 80 from the mold —A—, to facilitate its insertion in the guide grooves of the wood frame, not shown.

As the staples are driven into the felt strip, the points, as —6—, at the ends of the 85 opposite arms of the staples, contact with the metal form —A—, and are deflected laterally to clinch them in the felt and thereby to prevent accidental removal of the staples therefrom, it being understood that 90 the pressure upon each staple, caused by the driving of the same into the felt, tends to compress the felt sufficiently to enable the points of the staples to engage and be deflected laterally by contact with the metal 95 form —A—, so that when the clinching is completed, the natural expansive force of the previously compressed felt strip, tends to draw the points —6— back into the felt away from the outer faces of the flanges 100 —4—, so that the opposite arms of the staples will be entirely concealed within the flanges —4—, leaving only the cross-bars of the staples exposed at the back of the felt and beyond the inner wall of the channel 105 —2—, thereby avoiding any liability of contact of the glass window with any portion of the staples.

It will be observed, however, that the flexibility of the felt enables the cross-bars of 110 the staples to be embedded in the back of the strip with their outer faces substantially

coincident with the corresponding face of said back, where held by the clinching of the inner ends —6— in the felt.

What I claim is:

- 5 1. A noiseless guide-strip for glass windows, comprising a strip of pliable fabric material, bent into U-shaped cross-sectional form, and staples driven from the back side of the pliable material into the opposite flanges thereof at intervals throughout the length of the strip to enable said strip to be flexed longitudinally while retaining its U-shaped cross-sectional form.
- 10 2. A noiseless guide-strip for glass windows, comprising a strip of felt, bent into

U-shaped cross-sectional form, and staples driven from the back side of the felt into the opposite flanges thereof at intervals throughout the length of the strip, to enable said strip to be flexed longitudinally while 20 retaining its U-shaped cross-sectional form, the points of the staples being clinched in the opposite flanges of the felt.

In witness whereof I have hereunto set my hand this 28 day of July, 1922.

GEORGE ALLEN REYNOLDS, JR.
